(57) **CLAIM**

The ornamental design for a combined bracelet and disposable fluid cartridge, as shown and described.

DESCRIPTION

FIG. 1 is a top left isometric view of a combined bracelet and disposable fluid cartridge in accordance with the present design;

FIG. 2 is a front elevation view thereof;

FIG. 3 is a left elevation view thereof;

FIG. 4 is a right elevation view thereof;

FIG. 5 is a rear elevation view thereof;

FIG. 6 is a top plan view thereof; and,

FIG. 7 is a bottom plan view thereof.

The broken lines in FIGS. 1 through 7 showing a bracelet represent environmental subject matter only and form no part of the claimed design. The other broken lines immedi-

(Continued)

ately adjacent to the shaded surfaces illustrate boundaries and do not form part of the claimed design.

1 Claim, 6 Drawing Sheets
